ABSTRACT

A device of the type known as heat pipe in which the heating means are inside the chamber and covered with a capillary structure in contact with the liquid to be evaporated.

Applicable notably to isothermal oven. FIG. 1.

HEAT TRANSFERRING DEVICE

The present invention relates to a heat transferring device of the type known under the name of heat pipe. Said devices comprise an closed space containing a small quantity of a liquid which is capable of evaporation.

Heating means applied locally to the said space produce the evaporation of a part of the liquid. A quantity of energy equivalent to the heat of evaporation is taken along by the vapour throughout the length of the space, the vapour condensing and giving off its heat of evaporation on the surfaces which are at a temperature lower than that of the surface of evaporation. The condensed liquid is brought back, due to gravity or by capillarity, in the zone of evaporation. In order to ensure the return of the liquid the walls of the space may be covered on the inside with a capillary structure in which the liquid is transported due to capillary forces.

In the known devices, the heating means are always on the outside. Consequently these devices have relatively large dimensions, whilst the heating means can easily be damaged.

Furthermore, in devices in which the inner surface of the outer wall of the space is covered at least partly with capillary structure difficulties are experienced in fixing said structure on a convex surface. Several fixing methods have thus been proposed — spot welding, soldering, holding by means of a helical spring and so on — without all this permitting a simple and rapid mounting.

It is the object of the invention to provide a heat transferring device of the kind described which remedies the above inconveniences.

According to the invention, the heating means are inside the space and covered with a capillary structure in contact with the liquid to be evaporated.

In these conditions, the liquid is distributed through the capillary structure throughout the surface of the heating element.

The return of the liquid toward the heating means may be augmented by capillary communication means which connect the capillary structure to the side wall of the space.

In other favourable embodiments: at least one capillary bridge is provided between the capillary structure and the side wall of the space.

a rod covered with a capillary system is provided and extends to at least a part of the length of the space, between the capillary structure and the side wall, in contact with these.

In a further favourable embodiment, a second capillary structure is provided throughout the length of the space on at least a part of the side wall.

In a favourable embodiment constructed as an isothermal oven, in which the space is formed by an outer tube and an inner tube, the heating element is constituted by a screened cable which is wound around the inner tube.

The invention will be described with reference to the drawings.

In the device shown in

FIGS. 1, 2 and 3 the heating means 1 inside the space A extends throughout the length or to a part of the length of the said space. It may be constituted by an electric heating element or by any other heating system

known per se such as a gas burner, chemical reaction, and so on, inside an envelope. The heating means 1 is covered with a capillary structure 3 in contact with the liquid 4 to be evaporated in such manner as to permit the flow of said liquid in the structure 3.

In order to facilitate the flow of the liquid towards the heating element, various arrangements may be used.

In FIG. 1, capillary bridges 5 are arranged at a distance from each other connecting the capillary structure 3 to the side wall of the space.

In FIG. 2, a rod of material compatible with the liquid and on which a capillary system 7 is present is arranged between the heating means 1 and the side wall 2 in contact with these. As the rod 6 extends throughout the length of the space the return of the liquid towards the heating means will be best ensured.

In FIG. 3 the heating means 1 is eccentrically arranged, in contact with the side wall. A second capillary structure 8 is also shown which is arranged (for example fixed by spotwelding) throughout the length of the space on a part of the wall (for example, according to a generatrix). Said second capillary structure permits of using the device even if the heating means is located at a point at the top of the device.

FIGS. 4, 5 and 6 show various arrangements of the evaporation zone of isothermal ovens for which the space A is defined by an outer tube 9 and an inner tube 10. The cross-section may be, for example, circular or rectangular.

In FIG. 4 the inner tube 10 is coaxially arranged with the outer tube 9 and preferably covered by second capillary structure 11. A screened heating cable 12 itself covered with capillary structure 13 is wound on at least a part of the inner tube 10. The connection to the outer tube 9 is ensured by the capillary bridges 14 arranged according to a generatrix which will preferably constitute the lower line of the device when same is to function with a horizontal axis.

In FIG. 5 the connection between the heating cable 12 and the outer tube 9 is obtained while interposing a rod 15, on which a second capillary system 15a is wound, against the inner tube 10.

In FIG. 6 the inner tube is arranged eccentrically in such manner that the cable 12 covered with the capillary structure 13 is held in contact with the outer tube 9.

The operation of the device as described is well known and the advantages of said devices are essentially due to simplification of construction and to their reduced dimensions.

In general, the choice of the liquid, of the materials and of the heating elements will depend upon the operating temperature which it is desirable to obtain, the quantity of liquid depending upon the capillary structure and slightly exceeding the saturation of same. The capillary structures are chosen and fixed according as the operation of the device is with, without, or against gravity, the examples given being non-limiting. In all these examples, the capillary structures are shown in the form of nets but it is to be understood that they may be replaced by any other type of structure currently used: wick, groove, and so on.

What is claimed is:

1. A heat transfer device comprising: an outer tube having an inner surface, an inner tube having length and an outer surface along said length, the inner tube situated within the outer tube, with an annular heat-

treatment space defined between said tubes, a quantity of vaporizable liquid within said space, an energizable heat source comprising a cable covered with a first capillary structure, a second capillary structure covering said outer surface of said inner tube, said cable being wound around said inner tube and thereby holding said second capillary structure against said outer surface of said inner tube.

2. A device according to claim 1 further comprising connection means connecting said second capillary structure to said inner surface of said outer tube. 10

3. A device according to claim 2 wherein said connection means comprises a rod extending axially in said annular space.

4. A device according to claim 3 wherein said rod is situated intermediate said second capillary structure and said cable such that said first capillary structure on said cable is held in contact with said inner surface of said outer tube.

5. A device according to claim 4 further comprising a third capillary structure covering said rod.

6. A device according to claim 1 wherein said inner tube is positioned eccentrically within said outer tube, whereby said first capillary structure covering said heating means is held in contact with and between said second capillary structure covering said inner tube and said inner surface of said outer tube.
